Attorney

UNITED STATES PATENT OFFICE.

JOHN B. CHRABKOW, OF CINCINNATI, OHIO.

SECTOR SWITCH.

Application filed October 14, 1924. Serial No. 743,571.

To all whom it may concern:

Be it known that I, JOHN B. CHRABKOW, a citizen of the United States, residing at Cincinnati, in the county of Hamilton and 5 State of Ohio, have invented certain new and useful Improvements in Sector Switches, of which the following is a specification, reference being had to the accompanying drawings.

10 This invention relates to multiple circuit switches, and more particularly to a multiple circuit switch adapted for use in connection with traffic controlling systems such as described in my co-pending application, 15 filed October 9, 1924, Serial No. 742,663.

An important object of the invention is 20 to provide in a switch of this character a switching element having a plurality of brushes for coaction with contacts carried by a suitable base, together with a handle the engagement of which to move the switch in a given direction will disconnect certain of the brushes and connect the other of the brushes, so that the switching element has 25 electrical engagement with only one set of contacts.

A further object of the invention is to 30 provide in combination with an operating member reciprocal upon a given track a pair of contact series associated with this track and brushes associated with the operating member automatically connected by operation of the operating member in a given direction to electrically engage with one or 35 the other of the series of contact.

A still further object of the invention is to 40 provide a device of this character which is simple in its construction and readily operated, and which will be durable and efficient in service.

These and other objects I attain by the 45 construction shown in the accompanying drawings, wherein for the purpose of illustration is shown a preferred embodiment of my invention and wherein:—

Figure 1 is a plan view of a switch constructed in accordance with my invention;

Figure 2 is a section on the line 2—2 of Figure 1;

50 Figure 3 is a section on the line 3—3 of Figure 2;

Figure 4 is a plan view of the free end of the operating bar with the cover removed;

55 Figure 5 is a bottom plan view of the free end of the operating bar;

Figure 6 is a view of the base of the

switch showing diagrammatically the connections to the contacts thereof in one use of the switch.

Referring now more particularly to the drawings, the numeral 10 indicates a sector-shaped base from the sides of which extend upwardly enclosing side walls 11 by means of which a top or cover 12 is supported. The base 10 is of insulating material which 60 has arranged upon its upper surface, adjacent its curved edge, a plurality of series of contacts, generally designated at 13 and 14. The series of contacts 13, in the present instance, includes a plurality of contacts 15 70 connected in parallel and a plurality of similar contacts 16 likewise connected in parallel and arranged alternately with the contacts 15. This series further includes a pair of main contacts 17 and 18. The series 14, 75 which is arranged inwardly of the series 13, consists of a pair of arcuately curved contacts 19 and 20, the contact 19 being connected in parallel with the contacts 15, and the contact 20 being connected in parallel with the contact 16. The contact series 14 further includes a pair of main contacts 21 and 22. Arranged at each end of the arcuate pair formed by the contact series 13 and 14 80 are stop members 23 and 24.

Pivoted upon the base, as at 25, is a hollow insulating operating bar 26, the pivot being at the center of arcuate curvature of the contact series 13 and 14, the free end of the bar being positioned to swing over these 90 contacts between the stops 23 and 24. The bar has secured to its under surface by securing elements 27 and 28 brushes 29 and 30 coating with the contact series 13 and 14 respectively. Pivoted to the operating bar 95 is a conducting lever 31, the upper end of which projects through an arcuate slot 32 formed in the cover 12 and is provided with an insulating handle 33. This insulating handle is so formed at its base that it may 100 rock from side to side with the pivot of the lever 31 as a center, this pivot extending longitudinally of the bar. It will be obvious that if the handle is engaged to move the bar in one direction in the slot, the pressure applied to move the bar in such direction, due to the frictional resistance set up by the brushes 29 and 30 in their engagement with the contacts, will cause the handle 33 to incline in the direction of movement and accordingly the lower end of the lever 31 to incline against the 105 110

2
direction of movement. The lower end of the lever is in the form of a switch blade and is adapted for connection with a source of current. In the present instance this is 5 accomplished by connecting the switch blade with a flexible wire 34 to the pivot 25, which in turn may be connected with the source of current. Secured to the inner side walls of the hollow operating bar are a pair 10 of blade contacts 35 and 36 with which the lower end of the lever alternately engages. These contacts are connected with the contact brushes 29 and 30, respectively, as shown.

15 To generally illustrate the operation of the device, I have shown the same in circuit with a set of traffic controlling signals in Figure 6. In this figure I have illustrated generally two intersecting streets 37 and 38. 20 Three signals, illustrating as incandescent lamps 39, 40 and 41, are employed for controlling traffic on the street 37. Three similar lamps 39^a, 40^a and 41^a are employed for controlling traffic on the street 38. The 25 lamp signals 39 and 39^a are warning signals and intended to indicate a proposed change of traffic. The lamps 40 and 40^a are danger signals indicating that traffic upon their respective streets must stop, and the 30 lamp signals 41 and 41^a are clear signals indicating that traffic upon their respective streets may proceed.

In the use of the device, the contacts 15 and 16 are connected to the warning signals 39 and 39^a. The contact 17 is connected with the contact 41 indicating clear upon the street 37, and the contact 18 with the contact 40^a indicating stop upon the street 38. The contact 21 is connected with the contact 40 indicating stop upon the street 37, and the contact 22 is connected with the signal 41^a upon the street 38. The arcuate contacts 19 and 20, being connected in parallel with the contacts 15 and 16, respectively, are accordingly connected with the traffic change signals 39 and 39^a of the streets 37 and 38.

With the connections as above described, the operation is as follows: Assuming the 50 operating bar to be in engagement with the stop 23 and the handle 33 to be inclining toward this stop, the brush 30 is rendered active and accordingly the contacts 21 and 22 actuated, with the result that the stop signal is illuminated upon the street 37, while the go signal is illuminated upon the street 38. After the handle is grasped to move the bar into engagement with the stop 55 24, the initial impulse given this handle will shift the handle and the lever 31 bringing the lower end of this lever into engagement with the blade contact 36. This blade contact being electrically connected with the brush 29, the brush 30 is disconnected and the brush 29 rendered active. As the move-

ment of the handle continues, the bar moves with the handle and the brush 29 sweeps over the contacts 15 and 16 alternately engaging the same, so that the traffic change signals of the streets 37 and 38 are alternately operated. Arriving at the stop 24, this brush comes into engagement with the contacts 17 and 18, with the result that the stop signal of the street 38 is actuated and the go signal of the street 37 actuated. After a predetermined period the movement of the handle is reversed, with the result that the position of the lower end of the lever is reversed and the brush 30 actuated. As the bar moves, the brush 30 sweeps over the contacts 19 and 20 continuously operating the change signals 39 and 39^a and finally coming into engagement with the contacts 21 and 22 which is the position originally described. It will thus be seen that by reciprocating the bar over a fixed path, the signal changes are effected, which changes are dependent upon the direction of operation of the bar.

It will be obvious that while the switch is primarily intended for use in connection with street signalling systems and, as shown, in such use is capable of a wide range of other uses, I do not limit myself to the specific arrangement hereinbefore set forth except as hereinafter claimed.

I claim:

1. In a switch, a member mounted to reversely operate over a fixed path, a pair of contact series mounted adjacent said path, 100 a pair of brushes carried by the member and each operating in continual engagement with one contact series and a handle for the member pivoted to the member forming the movable contact with a switch having movable and stationary contacts, the stationary contacts of said switch being electrically connected with said brushes.

2. In a switch, a member mounted to reversely operate over a fixed path, a pair of contact series mounted adjacent said path, a pair of brushes carried by the member and each cooperating with one contact series, and means for rendering the brushes active comprising a handle for the member, said handle being mounted for oscillation upon the member and upon initial movement thereof to impart movement to the member in a given direction and inclining in such direction, said means for rendering the brushes active being operated by the inclination of the handle.

3. In a switch, a bar adapted to be reversely operated upon a fixed path, a pair of contact series arranged adjacent said path, a pair of brushes carried by the bar and each continuously engaging one of said contact series, a pair of blade contacts carried by the bar, a blade pivoted upon a pivot transversely of the line of movement of the 125 130

bar and adapted to alternately engage said contacts, each of said blade contacts being electrically connected with one of said brushes, and a handle for operating the bar 5 secured to said blade.

4. In a switch, an insulating base, a bar pivoted to swing over the base in parallel relation thereto, a pair of arcuately curved contact series arranged beneath the end of the 10 bar and over which the bar operates, a pair of brushes carried by the bar and engaging said contact series, a blade pivoted to the bar and electrically connected with the pivot of the bar, a handle secured to one 15 end of said blade, and a pair of blade contacts with which the opposite end of the handle connects, said blade contacts being electrically connected with said brushes, the pivot of said blade extending longitudinally of the bar whereby initial movement imparted to the handle to move the bar in either direction causes oscillation of the blade disengaging the same from one of said blade contacts and engaging the same with the other of the blade contacts.

5. In a switch, an insulating base, a bar 20 pivoted to swing over the base in parallel relation thereto, a pair of arcuately curved

contact series arranged beneath the end of the bar and over which the bar operates, a pair of brushes carried by the bar and engaging said contact series, a blade pivoted to the 25 bar and electrically connected with the pivot of the bar, a handle secured to one end of said blade, and a pair of blade contacts with which the opposite end of the handle connects, said blade contacts being electrically 30 connected with said brushes, the pivot of said blade extending longitudinally of the bar whereby initial movement imparted to the handle to move the bar in either direction causes oscillation of the blade disengaging the same from one of said blade contacts and engaging the same with the other of the blade contacts.

In testimony whereof I hereunto affix my signature.

JOHN B. CHRABKOW.
